(57) **CLAIM**

The ornamental design for a vehicle gratitude light display, as shown and described.

DESCRIPTION

FIG. 1 is an isometric view of a vehicle gratitude light display showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof; and,

FIG. 8 is a front perspective view shown in an environment of use.

The broken lines in the drawings depict environment and portions of the vehicle gratitude light display that form no part of the claimed design.
